STAPLING MACHINE

James Balton, Baltimore, Md.

Application October 17, 1947, Serial No. 780,311

6 Claims. (Cl. 140—11)

1

This invention relates to stapling machines for binding wires together and has particular reference to devices of this character for automatically stapling in alignment a plurality of aligned wires in coil spring constructions employed in mattresses, cushions, upholstered furniture, etc.

In the manufacture of these spring structures, a pair of coils are joined at their top and bottom end convolutions with a straight wire or rod disposed between the end convolutions of the adjacent coils, the three wires being stapled together so that the wires are in alignment within the staple. This stapling process has been performed, heretofore, largely by hand, and the mechanical expedients used to relieve hand operation have been found wanting in that they do not provide an effective, rapid, automatic method and means for yielding a good stapling job.

Among the objects of this invention is to provide a stapling machine which overcomes the foregoing objections incident to the prior stapling devices and which binds the wires in a neat, tight, effective manner, both rapidly and automatically.

A further object of this invention is to provide a machine for automatically stapling in alignment a plurality of aligned wires by cycles of operations involving regulation of the feed of a metal ribbon from which staple blanks are cut, timing the cutting of the staple blank, shaping of the staple blank into a U-shape in position about the wires to be gripped and bound in alignment, and successive clinching of the end of each leg of the staple over the wires, thus yielding a solid structure with the staple held tightly and snugly against and about the wires.

A more specific object of this invention is to provide an automatic stapling machine wherein cam-controlled, power-applied mechanical elements or members will operate synchronously to effect the desired sequence and cycles of operations involving regulation of the feed of a metal ribbon from which staple blanks are cut, timing the cutting of the staple blank, shaping of the staple blank into a U-shape in position about the wires to be gripped and bound in alignment, and successive clinching of the end of each leg of the staple over the wires in tight and snug hold.

Other, further and more specific objects of this invention will become readily apparent to persons skilled in the art from a consideration of the following description when taken in conjunction with the accompanying drawings wherein:

Fig. 1 is a side elevation of the machine.
Fig. 2 is a plan view.

2

Fig. 3 is a longitudinal section on line 3—3 of Fig. 2.

Fig. 4 is a cross section on line 4—4 of Fig. 3.

Fig. 5 is a fragmentary side view and taken from the opposite side of Fig. 1.

Fig. 6 is a section on line 6—6 of Fig. 5.

Fig. 7 is a section on line 7—7 of Fig. 5.

Fig. 8 is a perspective view of the bar for disengaging the clutch.

Fig. 9 is a perspective view of the dog-carrying block in the clutch operating mechanism.

Fig. 10 is a section on line 10—10 of Fig. 4.

Fig. 11 is a horizontal section on line 11—11 of Fig. 3.

Fig. 12 is a section on line 12—12 of Fig. 3.

Fig. 13 is a section on line 13—13 of Fig. 3.

Figs. 14 and 15 are perspective views of the two complementary parts of the stationary blade of the shear for cutting the tape.

Fig. 16 is a perspective view of the upper tape feeding roll and its operating mechanism.

Fig. 17 is a perspective view of a block for separating the feed rolls.

Fig. 18 is a perspective view of the tape cutting and bending punch.

Fig. 19 is an elevation of the disc and its cam track.

Figs. 20 to 27 are sectional views through the anvil and punch of my device showing the successive steps in forming the loop.

Fig. 28 is a section on line 28—28 of Fig. 3.

Fig. 29 is a perspective view of portions of two springs and a wire secured together by a staple.

The machine comprises a frame 2 on top of which is secured a table 4. Approximately midway between the floor and the table is a cross member 6 on the frame 2 to which are bolted two angle irons 8, the latter also being supported by a brace 10 extending rearward from the back 40 of the frame.

Connecting the forward ends of the bars 8 is a pin 12 on which is pivotally mounted a bracket 14, a motor 16 being in turn secured to the bracket and capable of a swinging movement about the pin 12. A pulley 18 on the motor shaft 19 is connected to another pulley 20 mounted on one end of a shaft 22 by a belt 24, the weight of the motor, tending to pivot about the pin 12, holding the belt taut. On the opposite end of shaft 22 is another pulley 26, smaller than pulley 20, and connected by a belt 28 to a relatively large pulley 30 on shaft 32. A sling or strap 34 is pivoted to the frame 2 at 36 and carries a brake band 38 which encircles the shaft 32 and applies a slight braking action at all times. The braking action may be

50
55

varied by the adjusting nut 40. A cam 42 and a disk 44, the latter having an internal cam track 46, are mounted on the shaft 32 for purposes hereinafter described.

The shaft 32 is mounted in the upper end of a lever 48, pivoted midway of its ends on a pin 50 and mounted in ears 52 at the rear of the frame. A bolt 54 is threaded in the frame and bears against the lower end 56 of the lever 48. By adjusting the bolt 54 the belt 28 may be tightened or loosened.

The pulley 30 is loose on the shaft 32 but may be connected thereto by a one-revolution clutch that will now be described. A foot lever or treadle 58 is pivoted to the rear of the frame 2, near the bottom thereof, and is provided with a pedal 60. The lower end of a link 62 is secured to the lever 58 and its upper end is secured to a member 64, the latter provided with a pin 66 projecting through a hole 68 in a plate 70 secured to the frame 2. A spring 72 fastened to a pin 74 in the member 64 and to a pin 76 in the plate 70 holds the foot lever in raised position. The hole 68 is larger than the pin 66 to permit depression of the foot lever, but limits its upward movement.

A block 78 is pivoted to the plate 70 by the bolt 80 and carries a spring-pressed dog 82 which engages in a notch 84 in bar 86, the latter sliding in guides 88 on the plate 70. Movement of the bar 86 is limited by a pin and slot connection 89. The bar 86 is urged upwardly by a spring 90. Mounted on the shaft 32 is a collar 92 keyed to the hub 94 of pulley 30 and provided with a series of semi-circular openings 96 around its inner periphery. The shaft 32 has an elongated bore 98. A pin 100 is pivotally disposed in this bore 98 and in a collar 102, and the collar 102 bears against the collar 92. Both collars as well as pin 100 and pulley 30 are held against axial movement by an inner flange 104 on shaft 32 and a washer 105 and nut 106 on the end of shaft 32. The pin 100 has a depending arm 108 that engages the upper end of bar 86 and is urged in a clockwise direction (as viewed in Fig. 5) about the shaft 32 by a spring 110. The pin 100 has a cutout portion 112, equal to the width of the collar 92, as clearly shown in Fig. 4. When the foot pedal is depressed it will pull down the bar 86, disengaging it from the arm 108. When this occurs the spring 110 will give a partial rotation to the pin 100 causing the portion having the face 112 to slab off to project beyond the periphery of the shaft and engage one of the notches 96 in collar 92, thereby effecting rotation of the collar and the pulley keyed thereto.

Since the bar 86 has a vertical movement and the dog 82 actuating it has an arcuate movement, the dog will ride out of the notch 84 shortly after the bar disengages from the arm 108, and the bar 86 urged by spring 90 will return to its original position and again engage the arm 108 after the pulley has made one revolution, regardless of whether the operator removes his foot from the pedal. This engagement of the bar 86 with the arm 108 will cause the pin 100 to turn in a counter-clockwise direction, thus disengaging it from collar 92. The brake band 38 prevents over running of the pulley.

Rotatably mounted in the outer ends of angle irons 8 is a roll of steel tape 114 about $\frac{3}{8}$ in. wide. The tape passes between the upper and lower feed rolls 116 and 118 which have engaging gears 119, one of which is shown in Figs. 75

2 and 16. The feed rolls are located at the rear of frame 2, directly below table 4. To enable the tape to be threaded between the rolls, the upper feed roll 116 is mounted in ears 120 of a bracket 122 bolted to the table as shown in Fig. 2 and the lower feed roll 118 is mounted in an arm 124 pivoted at 126 to bracket 122 and pressed upwardly by a spring 128, causing the rolls to engage the tape. The outer end of arm 124 is bifurcated and rotatably mounted therein is a separator block 130 having a handle 132. The upper part of the separator block 130 is also bifurcated and the upper horizontal faces 134 of the bifurcations are disposed just below a pin 136 secured in the ears 120 of bracket 122. Notches 138 are provided in the faces 134 adjacent their rear edges. When the handle is turned clockwise, as seen by Fig. 3, the faces 134 will engage the pin 136 causing a camming action, thus swinging the arm 124 about its pivot and moving the roll 118 away from roll 116. This allows free movement of the tape between the rolls. If the block 130 is swung until the notches 138 engage the pin 136, the arm 124 will be locked in a lowered position and the tape can be freely adjusted.

To feed the tape between the rolls a lever 140 is pivoted intermediate its ends on a shaft 142 (Fig. 3), the lower end of the lever carrying a roller 144 engaging the face of cam 42. A horizontal link 146 is pivotally connected at one end to the upper end of lever 140 and at its other end is pivotally connected to a plate 148, the latter carrying a spring-pressed dog 150 engaging ratchet 152 secured to the shaft 153 carrying the upper roll 116. The plate 148 is also pivoted on this shaft 153. The roller 144 is urged in contact with the cam 42 by a spring 154, bearing at one end against the head of a rod 155, which passes through the spring and is secured to the lever, and at its other end against a yoke 156 secured to the frame. The length of the stroke of the lever may be varied by a collar 158 threaded on the rod and a lock nut 160. It will thus be seen that as the roller 144 follows the cam 42 the roller 116 will be given a step by step rotation and will feed the tape forwardly.

After leaving the feed rolls the tape passes slightly upwardly and forwardly through a guide tube 162 and through a groove in a guide plate 164 secured to the table. Another tube 166 guides the tape from the plate 164 to what may be termed the stationary part of the shear, more fully described hereinafter.

A roller 168 bears against the cam 42 below its shaft 32 and is carried by a lever 170 pivoted on a shaft 172 carried in the frame 2. The roller is held against the cam by a spring 173. The forward end of the punch lever 170 is pivotally connected to a two-part adjustable knuckle 174, the upper end of the knuckle being connected with and imparting vertical movement to a rod 176 guided in a bearing 178 on the frame 2, a key 180 in the bearing preventing rotary movement of the rod. A punch 182 is secured in the upper end of the rod 176 by a set screw 184 and the upper end of the punch has a transverse slot 186 for a purpose which will later appear. A pressure rod 188 slides in a bore 190 in the punch 182 and has a head 192 that moves in a counter bore 194, the rod 188 being urged upwards at all times by a spring 196 also disposed in the counterbore and bearing against the head 192. The spring 196 is held in place by a plug 198.

A block 200 is secured to the table 4 and has a

suitable opening 202 to receive and form a guide for the punch 182. Upper and lower die blocks 204 and 206 are secured to the block 200 and complete the guide for the punch. The upper die block 206 has an opening 208 to receive a tongue 210 on the lower die block 204. The length of the tongue 210 is less than the depth of the opening 208 and there is thus provided a space slightly greater than the thickness of the tape. The tape 114 is fed through this space and its forward edge bears against the base of the U-shaped opening 202 in block 200, as clearly shown in Fig. 20.

An anvil 212 is positioned slightly above the table 4 and has a downwardly projecting portion 214 passing through a slot 216 in the table and fastened in a slot 217 in a slide 218 moving in guideways 220 on the under side of the table. Guide bars 221 hold the slide in the guideway. Horizontal movement of the bar 86 and anvil 212 is provided by a bell crank lever 222 pivoted on a shaft 224 in the frame, the lever at one end having a roller 226 riding in a cam track or groove 228 in the disk 44 and the other end of the lever being connected to an adjustable knuckle 230. The knuckle is pivoted to a projecting member 232 by a removable pin 233, the member 232 being securely fastened to the slide 218. It will be clear therefore that as the lever is rocked by the action of the cam track on the roller a forward and backward movement will be imparted to the slide and anvil.

The anvil 212 above the table is bifurcated and an ironing finger 234 is located between said bifurcations and is adjustable with relation to the downwardly projecting portion 214 by a vertical bolt 236. The ironing finger 234 has a vertical slot 238 and a bolt 240 passes through this slot 238 and the bifurcations of the anvil 212. A collar 241 is secured to bolt 236 and bears against the under surface of the ironing finger 234. By this construction the ironing finger 234 may be adjusted vertically by the bolt 236 to take care of slight variations in the thickness of the tape 114. When the ironing finger 234 is in the desired position, it is locked by bolt 240. The pins 242, set in complementary grooves in the bifurcations of the anvil 212 and ironing finger 234, as shown in Fig. 11, guide the ironing finger in its vertical adjustment. The bifurcations and ironing finger extend horizontally from the portion 214 with their under surfaces just above the table 4, and the ironing finger 234 has a slot 244 in the under surface. This is the part that does the actual folding of the staple, as the latter is held in the punch 182.

Blocks 246, having arcuate surfaces 248 are fastened to the table by screws 250 and serve to position one of the springs to be fastened by the staple.

In the operation of the machine a spring 252 is positioned on the table by the blocks 246 and a connecting rod 254, usually of the same diameter as the spring, is placed against it, as shown in Figs. 12 and 29. Offsets 256 in the rod indicate to the operator the positioning of the rod. A second spring 258 is then brought against the rod, as also shown in Figs. 12 and 29. With both springs and the rod held under the anvil 212, the machine is ready for a stapling operation.

The operator places his foot on the pedal 60 which will operate the clutch to rotate shaft 32. This will turn cam 42 keyed on the shaft and operate the feed rolls 116 and 118 through lever 140

and link 146 to bring the tape to the position shown in Fig. 20. Continued rotation of the cam 42 will start raising the punch 182 and the cam track 228 will operate the lever 222, moving the anvil to the position shown in Fig. 21. Continued upward movement of the punch will shear the tape 114 and carry the cut portion upward as shown in Fig. 22, while at the same time the anvil continues its movement.

When the anvil and punch reach the position shown in Fig. 23, the horizontal movement of the anvil ceases, due to a dwell in the cam track 228. The punch continues upward, and as the springs and rod are held by the under surfaces of the bifurcations of the anvil 212, the staple will start to bend as indicated in Fig. 24. The pressure rod 188 will start to depress but will hold the springs and rod firmly against the under surface of the anvil and continued upward movement of the punch will form the staple into a U, with its base, and the springs and rod, located in the slot 186 in the punch as shown in Fig. 25. The springs and rod will be snugly and tightly held in the base of this U.

The upward movement of the punch now ceases and a forward movement of the anvil again takes place. The under surface 260 of the ironing finger 234, to the rear of the slot 244, is spaced above the under surfaces of the bifurcations of anvil 212 a distance equal to the thickness of the tape and, as the anvil moves forward, the rear edge of slot 244 will engage the rear unturned leg of the staple and bend it down on the springs and rod, as shown in Fig. 26. The surface 260 will hold the leg after it is bent, as also seen in Fig. 26.

Due to the shape of cam track 228, the anvil will now start to retract its movement and, as it does, the forward edge of slot 244 will engage the other or front leg of the staple and bend it down on the first leg as clearly seen in Fig. 27. The forward surface 262 of ironing finger 234 is spaced above the under surfaces of the bifurcations of the anvil 212 a distance equal to twice the thickness of the tape and is higher than the surface 260 by a distance equal to the thickness of the tape so that on the return movement it can press the leg of the staple down on the previously bent leg. This completes the stapling operation. The parts return to the position shown in Fig. 20, the stapled springs and rod removed, others put in position, and the machine is ready to repeat the operation.

By reference to Figs. 25, 26 and 27, it will be seen that in the most outward position of the punch 182 there is a small clearance between the plane of the outer face of the punch and the under surfaces of the bifurcations of the anvil 212. This is a preferred condition of operation, for, in addition to the wires being held in close and snug embrace by the staple, tight clinching of the staple about the wires is assured through adequate utilization of the pressure of the ironing finger upon the staple and wires as this finger slides parallel to the aligned wires.

As above stated, the ironing finger 234 can be adjusted vertically for variations or different thicknesses of tape and also for variations in tightness and pressure of staple on the wires. Adjustment of knuckle 174 will take care of slight variations in the thicknesses of the springs 252 and 258 and rod 254. The pressure rod 188 is an important element as it keeps the springs bearing firmly against the under surface of the anvil, so that no vertical movement can

occur. Horizontal movement of the parts being operated on is prevented as they are held in the slot 188 of the punch.

By employing the process and apparatus set forth above, my novel stapling operation is carried out automatically and results in the staple being held snugly and tightly about the wires with practically no clearance between the staple and wires.

The present invention is not limited to the specific details set forth in the foregoing examples which should be construed as illustrative and not by way of limitation and, in view of the numerous modifications which may be effected therein without departing from the spirit and scope of this invention, it is desired that only such limitations be imposed as are indicated in the appended claims.

I claim as my invention:

1. In a stapling machine for wires, a table, a bifurcated anvil in reciprocating relation to said table and an ironing member connected to said anvil and disposed between the bifurcations, said ironing member having a pair of legs spaced from each other and providing with said bifurcations the walls of a cavity overlying said table, one of said legs of the ironing member having a face spaced from the faces of the bifurcations of said anvil a distance substantially equal to the thickness of the staple and the other leg having a face at a distance from the faces of the bifurcations of said anvil substantially equal to twice the thickness of the staple.

2. In a stapling machine for wires, a table, a bifurcated anvil in reciprocating relation to said table and an ironing member connected to said anvil and disposed between the bifurcations of said anvil, said ironing member having a pair of legs spaced from each other and providing with said bifurcations the walls of a cavity overlying said table, one of said legs of the ironing member having a flat face spaced from the faces of the bifurcations of said anvil a distance substantially equal to the thickness of the staple and the other leg having a flat face at a distance from the faces of the bifurcations of said anvil substantially equal to twice the thickness of the staple.

3. In a stapling machine for wires, means for clinching the staple about the wires, said means comprising a bifurcated anvil and an ironing member connected to said anvil and having two ironing faces spaced from each other and disposed to reciprocate substantially parallel to a table, the path of movement of one of said faces being at a distance from the faces of the bifurcations of said anvil substantially equal to the thickness of the staple and the path of movement of the other face being at a distance from the faces of the bifurcations of said anvil substantially equal to twice the thickness of the staple.

4. In a stapling machine for wires, means for clinching the staple about the wires, said means comprising a table and a bifurcated anvil adapted to hold a plurality of wires in taut state, and an ironing member connected to said anvil and comprising a pair of ironing faces spaced from each other and providing an intermediate cavity to receive the legs of the U-shaped staple preliminary to clinching, said ironing member having one of its ironing faces spaced from said table a distance greater in length than the spacing of said other face of the ironing member from said table by an amount equal to the thickness of said staple.

5. The combination claimed in claim 4 and having means for moving the ironing member substantially parallel to the wires.

6. The combination claimed in claim 4 wherein the ironing member is disposed between the bifurcations of the anvil.

JAMES BALTON.
